A. S. CUMMINGS,

COMBINED LOCK AND ALARM.

APPLICATION FILED MAR. 28, 1921, RENEWED JAN. 4, 1922.

1,423,554.

Patented July 25, 1922.

ANDREW S. CUMMINGS, INVENTOR.

By Watson E. Coleman
his ATTORNEY.

UNITED STATES PATENT OFFICE.

ANDREW S. CUMMINGS, OF SOUTH TACOMA, WASHINGTON.

COMBINED LOCK AND ALARM.

1,423,554.

Specification of Letters Patent. Patented July 25, 1922.

Application filed March 28, 1921, Serial No. 456,074. Renewed January 4, 1922. Serial No. 527,050.

To all whom it may concern:

Be it known that I, ANDREW S. CUMMINGS, a citizen of the United States, residing at South Tacoma, in the county of 5 Pierce and State of Washington, have invented certain new and useful Improvements in Combined Locks and Alarms, of which the following is a specification, reference being had to the accompanying drawings.

This invention relates to a combined lock and alarm and has for its object to provide a device of this character capable of being readily applied to either a window or a 15 door.

Another object is to provide a device of this character wherein any movement of the lock will cause operation of the alarm.

Another object of the invention is to provide a device of this character wherein the alarm serves as a weight for the lock to hold the same in its locked position.

A still further object of the invention is to provide a device of this character which permits the upper and lower sash of a window to be maintained in an open position and yet prevent the entrance of an unauthorized person.

A still further object of the invention is 30 to provide a lock of this character which is adapted to be disposed at a substantial point of the window namely the junction of the horizontal and vertical rails of the sash and so arranged that it is impossible for the lock 35 to be operated from the outside.

With the above and other objects in view, the invention consists in the improved construction and arrangement of parts to be hereinafter more particularly described, 40 fully claimed and illustrated in the accompanying drawings, in which:

Figure 1 is a fragmentary side elevation of the upper and lower sash showing the invention applied.

Figure 2 is a front elevation of the structure shown in Figure 1.

Figure 3 is a detailed view of the pawl.

Figure 4 is a side elevation of another form of pawl.

Figure 5 is a side elevation of the pawl in its unlocked position.

Figure 6 is a front elevation of another form of bracket.

Referring to the drawings, A designates 55 the lower sash of a window and B the upper sash. It is of course obvious that the device is not limited in use to a window but

may be used to entire satisfaction in connection with a door or any closure member. Carried by one of the vertical rails of the 60 upper sash adjacent the lower horizontal rail thereof is a plate 5 having bevelled teeth 6 projecting therefrom to provide a rack, means being provided at the end of the plate for securing the same to the sash. By providing a plurality of teeth, the sash may be 65 held in various adjusted positions.

Carried by the upper horizontal rail of the lower sash A adjacent the plate 5 is a bracket 7 comprising a supporting plate 8, 70 said supporting plate having a depending plate 9 provided with openings 10. The bracket engages the end face of the sash, while the plate 9 engages the vertical rail thereof. Projecting from the upper portion 75 of the plate 8 is a pair of spaced lugs 11. It will be noted that the ears 11 also project from one end portion of the plate, that is, the end portion at the junction of the plates 8 and 9. A lug 12 is carried by the 80 plate 8 adjacent the ears 11 and is adapted to extend inside of the window casing or molding to prevent the bracket from being torn off the sash. It is of course obvious that these brackets may be made with right 85 or left hand projecting ears so that the device may be used on either side of the window sash.

A pawl or shank 13 is provided, the end 14 of said shank being canted to provide a 90 stop 15. The end 16 is canted and adapted to engage the plate or rack 5. The end 14 is also provided with an opening 17 adapted to receive a pivot pin 18 which is supported by the ears 11. A bearing 19 projects from 95 one side face of the pawl adjacent the canted portion 16, the purpose of which will be hereinafter described.

An alarm 20 is carried by said side face of the pawl, the alarm being provided with 100 means for sounding the same. This means is operated by a trigger 21 which extends into the alarm and is also slidably mounted in the bearing 19. It will be noted that the end 22 of the trigger is bowed outwardly 105 and in the direction of the canted end 16 so that upon engagement of the canted end 16 with the rack the trigger will also be positioned to engage the rack in a similar manner. The alarm 20 also performs another 110 function, namely, that of serving as a weight for the pawl 13 to urge the same toward the rack when the pawl has been swung by the operator into its locked position.

In order to render movement of the pawl 13 impossible when the sash B is moved by an unauthorized person, there is provided a novel locking mechanism consisting of a key 23 having one end formed into a finger piece 24. One longitudinal edge of the key, is canted as at 25 toward the finger piece 24 to provide an inclined surface adapted to engage the end 15 of the pawl 13. A spring 26 has its end 27 secured to the intermediate portion of the key 23. The opposite end portion 28 of the spring is secured to the rail of the lower sash by fastening means 29, the extremity of said end portion 28 being imbedded in the rail of the sash.

When it is desired to lock the sash, the pawl 13 is swung toward and into engagement with the rack 5, as shown in Figure 1. The key 23 is then inserted between the plate 8 and the end of the pawl and is urged inwardly of the bracket by means of the spring 26. The wedge, however, does not prevent the pawl from moving slightly so as to permit operation of the alarm. It will be noted that the pawl 13, in view of the width of the sash A, is maintained in an inclined position so that it is impossible for the pawl to become accidentally disengaged from the rack. In addition to this the weight of the alarm 20 serves to urge the pawl toward the rack. Should any force be applied to the window in order to disengage the pawl from the rack, the relative movement of the pawl and the rack will depress the trigger 21, thereby sounding the alarm. It is of course obvious that even if the sashes A and B are moved it will not cause disengagement of the pawl from the rack but instead will urge the pawl into binding engagement or frictional engagement with the rack so that the pawl will resist all efforts to open the sash. To unlock the sash and permit the same to be raised or lowered, the key 23 is disengaged from the bracket and positioned in engagement with the outer edge of the pawl 13, as shown in Figure 5, the stop 26 maintaining the pawl substantially in a vertical position to prevent engagement of the pawl with the rack 5 when the sash is being raised or lowered. If desired, the sash may be maintained in an open position to permit ventilation of the room and at the same time locked in this position by means of a pawl by constructing the rack 5 relatively long to permit the pawl to engage the rack at any point, it being impossible for an unauthorized person to enlarge the opening beneath and above the sash in order to gain an entrance, even after the alarm has been sounded.

In Figure 4, a modified form of the invention is shown. In this form the canted portion 15 is removed and a leaf spring 30 secured to the plate 9, the end of the spring 65 being disposed in engagement with the pawl

to urge the same toward the rack. As shown in Figure 6, the plate 9 of the bracket may be removed so as to permit the device to be used in connection with a door, the bracket being secured to the door and the rack 5 to the floor. The operation is exactly the same as the form of device applied to the window sash.

From the foregoing it will be readily seen that this invention provides a novel device which not only serves as a lock for a door or window, but also as an alarm, the alarm being so arranged that it does not interfere with the operation of the lock and vice versa. Furthermore, its construction is simple and in view thereof, it can be readily applied by an unskilled person.

What is claimed is:—

1. A lock and alarm of the character described comprising a rack carried by a support, a pawl carried by a second support and adapted to engage the rack, an alarm carried by the pawl, and trigger means carried by the pawl for actuating the alarm, said trigger means being disposed in engagement with the rack.

2. A lock and alarm of the character described comprising a stationary rack, a pawl pivoted to a movable member and arranged to engage the rack, an alarm carried by and movable with the pawl, and an actuating trigger for the alarm, said trigger being movably mounted on the pawl and movable with the pawl to engage the rack and movable independently of the pawl to activate the alarm.

3. A lock and alarm of the character described comprising a rack carried by a support, a bracket carried by a second support, a pawl pivoted to the bracket, and a key movably connected to the second mentioned support and adapted to be disposed between the pawl and the bracket.

4. A lock and alarm of the character described comprising a rack carried by a support, a bracket carried by a second support, a pawl pivoted to the bracket, spring means carried by the second mentioned support, a key carried by said spring means and adapted to be disposed between the pawl and the bracket to limit movement of the pawl.

5. A lock and alarm of the character described comprising a rack carried by a support, a bracket carried by a second support, a pawl pivoted to the bracket, spring means carried by the second mentioned support, a key carried by said spring means and adapted to engage one longitudinal edge of the pawl in parallel relation thereto to prevent engagement of the pawl with the rack through the medium of the spring means.

In testimony whereof I hereunto affix my signature.

ANDREW S. CUMMINGS.
